UNITED STATES PATENT OFFICE.

DAVID VARIUS KAUFMAN, OF NEW YORK, N. Y., ASSIGNOR OF ONE-HALF TO
ISIDORE SCHMERTZLER, OF NEW YORK, N. Y.

INK DISTRIBUTOR.

Application filed May 25, 1921. Serial No. 472,380.

To all whom it may concern:

Be it known that I, DAVID V. KAUFMAN, a citizen of the United States, and a resident of the city of New York, borough of Manhattan, in the county and State of New York, have invented a new and Improved Ink Distributor, of which the following is a full, clear, and exact description.

This invention relates to printing presses and particularly to an improved attachment therefor, and has for an object to provide a construction which may be bodily applied and removed at any time without injuring the attachment or the press.

Another object in view is to provide an improved ink distributing construction whereby all parts of a sheet may be supplied with substantially an even quantity of ink and thereby cause pictures and other representations requiring an appreciable amount of ink to all appear alike when printed.

A further object of the invention is to provide an attachment for printing presses which may be readily applied and removed at any time and which is constructed with one or more distributing rollers adapted to engage one or more of the permanent ink distributing rollers of the press and continually act as distributing members for distributing ink over said permanent rollers during the operation of the press.

An additional object is to provide an attachment for printing presses having one or more distributing rollers which reciprocate as they rotate.

In the accompanying drawings—

Figure 1 is a front view with certain parts broken away disclosing one embodiment of the invention, said broken portion being taken on line 1—1 of Figure 2.

Figure 2 is a sectional view through Figure 1 on line 2—2.

Figure 3 is a detail fragmentary sectional view through Figure 2 on line 3—3.

Figure 4 is a view similar to Figure 1 but showing a slight modified form of the invention.

Figure 5 is a sectional view through Figure 4 on line 5—5.

Figure 6 is a view similar to Figures 1 and 4 but showing an additional modified form of the invention.

Figure 7 is a sectional view through Figure 6 on line 7—7.

In all forms of modern printing presses

some form of inking device is provided which will automatically ink the type. In order that the ink may be properly distributed over the surface, it has become the practice to provide two or more distributing rollers, sometimes acting alone and other times in connection with auxiliary means for securing efficient inking of the type. In the present invention, means have been provided which are designed to be readily attached or removed at any time and to assist the ordinary ink rollers now in use in providing an even distribution at all times without supplying ink in too large quantities.

In Figures 1, 2 and 3 one construction of attachment is shown which is particularly adapted for a certain type of press having a comparatively large bar 1 forming part of the distributing mechanism which mechanism also includes the distributing rollers 2, 3 and 4. These members are all now in common use and form no part of the present invention. In order that applicant's rollers or distributing members 5 and 6 may properly function they are carried by end frames 7 and 8, each of said frames having a bifurcation 9 as shown in Figure 2 whereby the bar 1 may be readily straddled and the device clamped thereto by one more set screws 10. These set screws are preferably locked by suitable nuts 11 whereby the device may be held rigidly in place and the rollers 5 and 6 in contact with the respective rollers 2, 3 and 4. Each of the frames 7 and 8 is provided with arms 12 and 13 and with a rounded depending nose 14 designed to permit the device to slide over any obstruction in case there is a slight swinging movement of the parts during rapid operation of the press. The arms 12 and 13 are each provided with a groove 15 in which a bearing box 16 is slidably mounted, said box having flat upper and lower sides and a round aperture for receiving the rounded projection 17 extending from the hub block 18, which hub block is round and over which the end of the respective tubes extend. Suitable rivets or other securing members 19 act to connect the rollers to their hub blocks 18. A pin 20 (Figure 3) is connected with each of the bearing boxes 16 and acts as an anchor for receiving one end of the respective springs 21 associated with each end of each of the rollers. These springs are connected to the respective arms 110

2
12 and 13 by suitable pins or screws 22 whereby the rollers 5 and 6 are resiliently held against the rollers 2, 3 and 4. Therefore, whenever the rollers 2, 3 and 4 are 5 rotated as they act in their usual capacity, the friction and adhesive quality of the ink will cause the rollers 5 and 6 to also rotate and continually distribute over rollers 2, 3 and 4 ink, said ink being taken off of the 10 rollers 5 and 6 to supply shallow spots on the rollers 2, 3 and 4 and in turn the rollers 2, 3 and 4 supply ink to the rollers 5 and 6. This is of great advantage where more than 15 one picture is to be printed on a single sheet and especially where said pictures are in alinement. If the rollers 5 and 6 are not used the first picture would take up most of the ink on the rollers 2, 3 and 4 as said rollers pass thereover so that a less quantity would 20 be provided for the second picture and, consequently, the second picture would be lighter than the first when printed. When the rollers 5 and 6 are used, said rollers will supply the deficiency in ink and, consequently, provide ample ink for the second 25 picture. In printing ordinary type the same is used though less noticeable as the type to first receive the ink will naturally receive the most ink and as the rollers pass 30 over the type less and less ink will be supplied. With an attachment which includes the rollers 5 and 6 all of the type are supplied with the same quantity of ink and, consequently, the printer's sheet will appear 35 the same color throughout.

In case it should be undesirable or unnecessary to use the attachment, the same may be easily and quickly removed by 40 loosening the set screws 10 and bodily lifting the device off of the press. This will leave the press in its usual shape or condition so that it may function in its usual manner. At any time the device may be 45 again placed on the press without altering the press or the device.

In Figures 4 and 5 a slightly modified form 50 of the invention is shown which embodies the same inventive idea as shown in Figure 1 but which is designed particularly for a different type of press or rather with a different type of distributing mechanism. As indicated in Figure 5 the distributing mechanism to which the structure shown in Figures 4 and 5 is to be used carries transverse rods or bars 23 and 24 and distributing rollers 25, 26, 27 and 28. Each of the frames 55 7' and 8' is provided with two bifurcations 9' and instead of having a set screw 10 a single pin 29 is used for each frame, said pin loosely fitting in suitable apertures in the projections forming the bifurcations 9'. However, these apertures are so positioned 60 that the pin 29 will snugly fit against the bars 23 and 24 and hold the frames comparatively rigid. In this form of the invention

tion the rollers 5' and 6' are each arranged to contact with two of the regular inking rollers of the press. In addition, these rollers reciprocate as they rotate. It is, of course, evident that the rollers 5 and 6 in 70 the preferred form of the invention may reciprocate also.

As shown in Figure 4 each of the rollers 5' and 6' is loosely mounted on the hub blocks 18' and carry a pin 30 which preferably carries a roller 31 fitting in a spirally arranged groove 32 in the tubular member 33, which tubular member is riveted or otherwise rigidly secured to the shaft 34. The shaft 34 at the ends is provided with 80 flattened sections 35 fitting into the respective bearing boxes 16' whereby said shafts may move laterally in the grooves 15 but cannot rotate. As the shells or rollers 5' and 6' are rotated by contact with the respective rollers 25, 26, 27 and 28, the action of the pin 30 and associated parts on member 33 will cause a reciprocation of the rollers 5' or 6' as the case may be. This reciprocation during rotation acts to more thoroughly distribute the ink especially where there is only one distributing roller on the attachment for two of the rollers on the printing press.

In Figures 6 and 7 a third form of the invention is shown which is really a slight modification from that shown in Figure 4. In this form of the invention each of the frames 7" and 8" is provided with a single bifurcation 36 for receiving a small rod 37 forming part of the ink distributing mechanism of the press, which ink distributing mechanism also includes the rollers 38, 39, 40 and 41. Where the press is provided only with one small rod 37 to which the device 105 may be attached, preferably two set screws 42 and 43 are used on each of the frames, said set screws being arranged to engage the rod 37 at opposite sides of a vertical central line whereby a good pinching action is secured and the device is prevented from any independent swinging movement. Aside 110 from this adaptation of the invention to the particular press the detail construction is identical to that shown in Figure 4 and, therefore, will need no additional description. It may be stated, however, that the frames in this form of the invention as well as the frames in the form shown in Figure 4 115 may be provided with any desired number of bracing bars 45 and 46 for holding the frames in proper position.

What I claim is:

1. In an ink distributor for printing 125 presses, a hinged supporting frame, rollers carried by said frame and adapted to engage the distributing rollers of the press, means for removably connecting said frame to the printing press, said rollers reciprocating in a direction transverse to the direction of the 130

frame, and resilient means acting on each of the rollers for yieldingly holding the same against the distributing rollers, said rollers and said frame being attachable on said 5 press as a unit.

2. An ink distributor attachment for printing presses comprising a plurality of frames formed with openings for engaging certain parts of the press, a set screw carried 10 by each frame for locking the frames in operative position, and a plurality of rollers carried by said frames for rotatively and reciprocatively distributing ink over the inking rollers of the press; together with means for 15 resiliently causing said rollers to engage the rollers of said press.

3. An ink distributing device adapted to be applied to a printing press adjacent the printing rollers thereof, said distributor 20 comprising a pair of frames, means holding said frames in spaced relation with respect to each other, one end of said frames being bifurcated to receive a portion of the frame of the press, means adjacent said bifurcated 25 ends for optionally attaching said frames to said press, a shaft journaled between said frames and carrying a cam adjacent its center and a collar adjacent each end thereof, and a sleeve having at its interior a projec- 30 tion adapted to co-act with said cam whereby the sleeve is caused to reciprocate on its longitudinal axis, said sleeve engaging with certain of said printing rollers.

4. An ink distributor for printing presses, 35 comprising a pair of attachable supporting

frame members, a rotatable roller carried by said frame members, a non-rotatable shaft slidably extending into said roller, a member rigidly secured to said shaft formed with a cam section, a projection carried by 40 said roller engaging said cam section, whereby when the roller rotates the cam section will cause a longitudinal movement of the roller, each of said frame members presenting pending grooved projections and a 45 bifurcated end, bolts extending into said bifurcated ends adapted to clamp said frames to said printing press, and bearing boxes slidably arranged in said grooves, said shaft being supported by said boxes. 50

5. An ink distributor for printing presses comprising a supporting frame adapted to be attached adjacent the printing rollers of a press, bars extending between said frames to hold the same in predetermined spaced 55 relation to each other, said frames presenting perpendicularly disposed projections, and a bifurcated end, each projection being formed with a groove, a bearing box slidably held in each groove, a spring secured 60 to the lower end of said groove and to said bearing box, a shaft extending between a pair of said bearing boxes, said shaft carrying adjacent each end thereof a collar adjacent the center thereof, a second collar 65 presenting a cam-groove, and a sleeve provided with an inwardly extending projection to engage said cam groove rotatably and slidably carried on said shaft.

DAVID VARIUS KAUFMAN.
